UNITED STATES PATENT OFFICE

CHARLES A. CAMPBELL AND JAMES D. CARTIN, OF WATERTOWN, NEW YORK, ASSIGNEES TO THE NEW YORK AIR BRAKE COMPANY, A CORPORATION OF NEW JERSEY

PUMP GOVERNOR

Application filed January 7, 1928, Serial No. 245,170. Renewed August 8, 1931.

This invention relates to fluid pressure regulators and will be described as embodied in a pump governor of the type used in railway air brakes, though some or all of the novel features are suited for general use and have particular utility in other air brake apparatus, for example feed valves.

This application is subordinate to our prior application Serial No. 180,043, filed 10 March 31, 1927, in which broad claims are presented to subject matter common to the two cases. Said prior application discloses the use of a heat radiating structure between the valve and valve motor, a leakage interceptor on the valve stem, means for directing spent air from the pressure motor in cooling relation with the heat intercepting means, and a dash pot for regulating the motion of the valve mechanism. The 15 broader claims to such features and combinations thereof, are presented in said prior application.

Referring to the invention as embodied in a pump governor, the important objects are 20 to limit or prevent the flow of steam or oil from the steam valve to the governor cylinder; minimize the transmission of heat from the valve to the cylinder (very important where superheated steam is used); cool the 25 governor cylinder by means of air discharged therefrom during operation; guide the steam valve in an improved manner; and insure smooth action of the governor cylinder by the use of a dash pot.

Various other objects and advantages will 30 be apparent from a consideration of the detailed description of the preferred embodiment of the invention illustrated in the accompanying drawings.

40 In the drawings,—

Figure 1 is a view principally in vertical axial section.

Fig. 2 is a plan view.

Fig. 3 is an enlarged fragmentary section 45 on the line 3-3 of Fig. 2.

The body of the steam valve is shown at 50 6. This is the valve that controls directly the fluid to be regulated and is typical of any valve for performing a similar function (cf. the main valve of a feed valve). The

valve seat is indicated at 7 and the valve at 8. In order to keep the pump warm when shut down, a bleed port 9 is formed in valve 8, as is usual. The valve body 6 is connected in such a way that steam flows through the 55 valve body in the direction of the arrow and thus exerts an opening tendency on valve 8.

Valve 8 is formed integrally with a tubular stem 11 which is guided in a bushing 12 shrunk into removable valve bonnet 13. 60

Stem 11 is externally grooved at 14 and bushing 12 is formed with a seat for conical valve 15, which is formed at the junction of stem 11 with a valve 8. The grooves 14 and valve 15 are provided to resist leakage of 65 steam or oil along the stem, particularly when valve 8 is positioned between seat 7 and the seat on bushing 12.

To divert such leakage as does occur, bushing 12 is formed with an annular internal 70 recess 16 above the range of travel of grooves 14 on the stem 11 and this recess is vented freely to atmosphere by way of ports 17, recess 18 in bonnet 13 and passage 19.

Within recess 16 the stem 11 is reduced or 75 shouldered as shown at 21, which has the effect of assisting to check flow along the stem through the guide passage in the top of bushing 12.

Supported in bonnet 13 by means of thin 80 fins 22 is cylinder housing 23 open at its lower end except for the sheet metal dust excluder plate 24 pressed to place in a recess provided for it. Plate 24 has an air vent port 25.

Seated on flange 26 in housing 23 and 85 pendant therefrom is cylinder bushing 27 which is spaced from the housing laterally and at its lower end, both throughout its circumference. A notch 28 is formed in the lower margin of bushing 27 to serve as a vent port even if the space below the lower margin of the bushing should become clogged.

The upper end of bushing 27 has a projecting flange 29 which seats on flange 26 and the upper face of flange 29 is grooved at 31 to keep gasket 32 from creeping. Gasket 32 seals the join between housing 23 and bushing 27 on the one hand and cap 33 on the other. 95

The cap 33 is formed with an annular projection 34 on its lower or inner side in which 100

is mounted a guide bushing 35 for hub extension 36 formed on piston 37. The hub extension and bushing serve as a dash pot to check sudden movements of the piston, which 5 works in cylinder bushing 27 and actuates main valve 8. This steadies the piston and permits the omission of a spring urging the piston 37 upward heretofore considered necessary.

10 Piston 37 has a packing ring 38 and piston rod 39. Rod 39 is formed with an integral collar 41 which engages the lower side of the piston, and the rod, extending upward through hub 36 is peened or riveted over at its 15 upper end to afford a rigid and permanently tight connection between the piston and rod. The lower end of rod 39 extends into and makes a close slip fit with the bore of tubular valve stem 11. It is in thrust engagement at 20 its lower end with valve 8, and the point of such engagement when the valve is closed is below the lower end of the valve guide in bushing 12.

Thus the valve and the piston guide each 25 the other and the construction is such that canting of each is prevented.

To permit a controlled discharge of pressure fluid (air) from the cylinder space above piston 37 a passage 42 (see Fig. 3) is cored 30 or otherwise formed in cap 33 and cylinder housing 23. This leads to the annular space surrounding bushing 27 so that the discharging air assists to keep bushing 27 and housing 23 cool.

35 At some point in this passage a choke port must be provided, and for illustration there is shown a choke port forming the subject of a prior application by Charles A. Campbell, Serial No. 236,340, filed Nov. 28, 1927, and 40 hence not claimed in the present application.

This choke structure includes a plug 43 having a vertical cup-like chamber 44 in which is mounted a free ball 45 of slightly smaller diameter. The interval between the 45 ball and the surrounding wall of the cup serves as the choke port. A passage 46 formed in plug 43 directs the outflowing pressure fluid eccentrically against the ball 45 so that the ball is given a rotary motion 50 which keeps the choke port clear of dust and other obstructions. The capacity of passage 46 exceeds that of the interval around ball 45 so that passage 46 has no regulatory action.

55 The pump governor chosen for illustration in the present case is of the well known duplex type and hence includes two diaphragm pin valves intended to function in alternation 60 with each other to maintain two different pressures. One diaphragm pin valve is shown in Fig. 1 in section and the other in elevation. As they are identical, except that they are adjusted to respond at different pressures, a description of one will suffice, identi-

cal parts of the two valves being given the same reference numerals.

Each valve is supported by an internally threaded cup-shaped base casting 51 threaded at 52 into cap 33 and having a passage 53 communicating with the space above piston 37, and a connection 54 by means of which connection is made with the main reservoir (not shown) or other volume whose pressure variations are to control the opening and closing of valve 8.

Supported in base 51 and sealed by gasket 55 is pin valve seat member 56. This is mounted in a recess which confines gasket 55, and has a flange 57 which seats on shoulder 58 in base casting 51. Flange 57 thus offers a firm support for diaphragm 59 clamped thereagainst by ring 61 and spring box 62 of usual form, which last is screwed into the internally threaded upper portion 85 of base 51.

Diaphragm 59 is open at the center as usual to receive a thrust plate and pin valve assembly of known form. This includes a thrust plate 63 guided at 64 in the spring box 62, a combined clamp screw and pin valve guide 65, threaded into the plate 63, a washer 66; a pin valve 67 and a spring 68 which holds the head of the pin valve 67 upward against thrust plate 63. Pin valve 67 contacts with port 69 in seat member 56 to open and close the same. Member 56 is ported to permit pressure fluid arriving by connection 54 to act against the lower face of diaphragm 59 and to discharge through port 69 when pin valve 67 opens the port.

Certain details of the pin valve structure above described are novel, but are not a part of the present joint invention and hence form the subject of a separate application.

Threaded in spring-box 62 is adjustable spring seat 71 which is locked by threaded cap 72. The spring seat sustains the upper end of loading spring 73 whose lower end carries the conical thrust member 74. Thrust member 74 engages thrust plate 63, a conical recess 75 being provided to position the thrust member and assure its centering in the thrust plate. The space above diaphragm 59 is vented to atmosphere by 110 port 76.

The two diaphragm actuated pin valves, commonly called "governor tops" are used in alternation with each other in a familiar manner to control the opening and closing 120 of the main valve 8. When both valves are closed pressure above piston 37 leaks away through choke port 44, 46 and steam pressure forces valve 8 open. If one of the pin valves 67 is opened by pressure arriving through its connection 54 and acting on diaphragm 59, the pressure fluid flows to the cylinder space above piston 37. If the rate of flow exceeds the capacity of the choke port 44, 46 the piston is forced down against 125 130

steam pressure which acts upward against valve 8, partially or wholly closing the valve 8.

The air escaping through the choke port 5 cools the bushing 27, housing 23 and the space below piston 37, and is finally discharged to atmosphere through port 25. In modern practice the use of superheated steam entails temperatures as high as 700° F. in 10 the valve body 6 and such temperature if allowed to prevail generally would affect adversely the desired smooth action of piston 37 and valve 8. The cooling effect of the discharging air, aided by partial thermal 15 isolation effected by the use of slender supporting webs 22, and the diversion of steam leakage through the use of vented chamber 16, is effective to keep the temperature of the piston and governor tops to the desired 20 relatively low value. The hand may be safely placed on cap 33 while valve body 6 is in the neighborhood of 700° F., hot enough to burn paint on the valve body.

The vented chamber 16 functions to divert 25 leakage. In pump governors the leakage is steam or steam and oil. In feed valves for air brakes, which are functionally and structurally similar the leakage is air and oil, and the oil, if it be permitted to enter the 30 regulating cylinder of any such device, causes mal-functions by gumming and causing the piston to stick. Thus the diverting chamber is a feature of particular importance in pressure regulators generally because of oil diversion 35 independently of the heat diverting function which it also performs in the pump governor above described.

What is claimed is:—

1. The combination of a valve body; a valve therein; a fluid pressure motor including a housing, a cylinder bushing spaced from said housing, and a piston arranged to actuate said valve, there being a vent port leading from the space to one side of said 40 piston within the bushing to the annular space between said housing and bushing and thence to atmosphere; and pressure responsive means for admitting pressure fluid at varying rates to act against said piston.
2. The combination of a valve body; a valve therein having a stem; a guide for said stem projecting from said body; a fluid pressure motor including a housing, a cylinder bushing mounted in and spaced from 45 said housing and a piston in said bushing arranged to actuate said valve through said stem, there being a vent passage leading from the cylinder space at one side of said piston, through the space between said housing and bushing and thence past said guide to atmosphere; and pressure responsive means for admitting pressure fluid at varying rates to act against said piston.
3. The combination of a valve body; a valve therein having a stem; a guide for said 50

stem projecting from said body; means in said guide arranged to intercept and discharge to atmosphere leakage flowing between said stem and guide; a fluid pressure motor including a housing, a cylinder bushing mounted in and spaced from said housing and a piston in said bushing arranged to actuate said valve through said stem, there being a vent passage leading from the cylinder space at one side of said piston through the space between said housing and bushing and thence past said guide to atmosphere; and pressure responsive means for admitting pressure fluid at varying rates to act against said piston.

4. The combination of a valve body; a valve therein having a stem; a guide for said stem projecting from said body; a fluid pressure motor including a housing, a cylinder bushing mounted in and spaced from said housing and a piston in said bushing arranged to actuate said valve through said stem, there being a vent passage leading from the cylinder space at one side of said piston, through the space between said housing and bushing and thence past said guide to atmosphere; a pressure responsive means for admitting pressure fluid at varying rates to act against said piston; and a heat radiating supporting connection between said 90 body and housing.

5. The combination of a valve body; a valve therein having a shouldered stem; a fluid pressure motor including a cylinder and piston and having a cylinder vent arranged to discharge pressure fluid in cooling relation with the cylinder, said piston being in thrust relation with said stem; a guide for said stem including a leakage interceptor comprising a vented chamber which embraces the shouldered portion of the stem; and pressure responsive means for admitting pressure fluid at varying rates to act against said piston.

6. The combination of a valve having a shouldered stem; a fluid pressure motor for actuating the valve through said stem; and means for intercepting leakage flow from the valve to the motor along the stem comprising a vented chamber distinct from said motor and through which the shouldered portion of the stem passes, and with the walls of which it makes slip fits on opposite sides of said shoulder.

7. The combination of a valve body; a valve therein having a hollow stem; a cylinder having a dash pot formed in one end thereof; a piston in said cylinder having a plunger extension working in said dash pot; a rod fixed in said piston and in thrust relation with and extending into said valve stem; a guide for said stem provided with leakage intercepting means comprising a vented chamber through and beyond which said stem passes; a heat radiating supporting 130

connection between said valve body and cylinder; and pressure responsive means arranged to vary the effective pressure in said piston.

- 5 8. The combination of a valve body; a valve therein; a fluid pressure motor including a housing open at its lower end, a cylinder bushing spaced from said housing, a piston working in said bushing and arranged
10 to actuate said valve, and a thin sheet metal closure for the open lower end of said housing, said closure being below said bushing and being ported, there being a vent passage from the space above the piston through the
15 space between the bushing and housing and thence beneath the bushing to the port in said closure; and pressure responsive means for admitting pressure fluid at varying rates to the space above the piston.
- 20 9. The combination of a valve body; a valve therein; a fluid pressure motor including a housing open at its lower end, a cylinder bushing spaced from said housing, a piston working in said bushing and arranged
25 to actuate said valve, and a thin sheet metal closure for the open lower end of said housing, said closure being below said bushing and being ported, there being a vent passage from the space above the piston through
30 the space between the bushing and housing and thence beneath the bushing to the port in said closure; pressure responsive means for admitting pressure fluid at varying rates to the space above the piston; and means for
35 supporting said housing comprising a plurality of slender blade-like struts extending between said housing and a portion of the valve body.

In testimony whereof we have signed our
40 names to this specification.

CHARLES A. CAMPBELL.
JAMES D. CARTIN.
